UNITED STATES PATENT OFFICE.

EPPA H. RYON, OF WALTHAM, MASSACHUSETTS, ASSIGNOR TO CROMPTON & KNOWLES LOOM WORKS, OF WORCESTER, MASSACHUSETTS, A CORPORATION OF MASSACHUSETTS.

BOBBIN-STRIPPER.

Specification of Letters Patent. Patented Oct. 27, 1914.

1,115,115.

Application filed December 12, 1913. Serial No. 806,317.

To all whom it may concern:

Be it known that I, EPPA H. RYON, a citizen of the United States, residing at Waltham, in the county of Middlesex and State of Massachusetts, have invented a new and useful Bobbin-Stripper, of which the following is a specification.

This invention relates to a bobbin stripper, especially designed to remove waste yarn from bobbins which have been ejected from an automatic filling replenishing loom of the so-called "feeler" type. The bobbins used in such looms are formed with a straight cylindrical portion near the butt, upon which portion is usually placed a preliminary winding or bunch of filling yarn before the regular winding is placed upon the bobbin. When in position in the shuttle, this cylindrical portion coacts with a feeler or detecting device upon the loom which controls the operation of the filling replenishing mechanism. As soon as the amount of yarn upon the bobbin has been reduced to a predetermined point, the feeler allows the replenishing mechanism to become operative to eject the used bobbin and to insert a full bobbin in place thereof. A small amount of filling yarn is necessarily left upon the ejected bobbin which must be removed therefrom before the bobbin can be again used. It has been the common practice to remove this waste yarn by cutting it from the bobbin with a knife or by loosening the yarn upon the bobbin by striking the nose of the bobbin sharply upon a rigid block, the yarn thereafter being slipped off of the end of the bobbin. These manual methods have been found to seriously injure the bobbins and to impair their length of service, and consequently certain mechanical devices have been designed to remove the waste from the bobbins. The more common type of such devices has consisted essentially of a combination of devices for gripping or supporting a single bobbin and a stripping device movable longitudinally of the bobbin to loosen the yarn and force it off from the end of the bobbin.

The object of the present invention is to increase the capacity and speed of operation and to improve the general efficiency of machines for performing the operation above described. With this object in view, a feature of the present invention contemplates the provision of bobbin supporting means

operable to support and guide the bobbins both before and after the stripping operation.

Another feature of the invention contemplates the provision of a plurality of gripping and stripping devices movable successively into operative position, thus eliminating loss of time during idle movements of the stripping devices. Provision is also made for feeding the supported bobbins intermittently to the gripping and stripping mechanism and the feeding device is mounted to yield without injuring itself or the work should the bobbin for any reason become caught in the path of the feeding finger. As a further safeguard I have provided a stop motion device by which the machine will be disconnected from its driving means if a bobbin is improperly positioned between the gripping devices.

To the accomplishment of the objects of my invention above referred to, the invention consists of certain devices, arrangements and combinations of parts which will be herein-after described and more particularly pointed out in the appended claims.

A preferred form of the invention is shown in the drawings in which—

Figure 1 is an end elevation of the bobbin stripper; Fig. 2 is a left hand side elevation of the machine shown in Fig. 1; Fig. 3 is a top plan view of the gripping and feeding mechanism; Fig. 4 is a cross section taken along the line 4—4 of Fig. 1; Fig. 5 is a detail of the gripping devices; Fig. 6 is a partial end elevation with certain parts omitted to show the stopping mechanism; Fig. 7 is a view similar to Fig. 6 showing the parts in a different position; Fig. 8 is a detail of certain parts of the stopping mechanism; and Fig. 9 is a perspective view of one of the stripper plates.

In the embodiment of the invention illustrated in the drawings, a frame 10 is provided upon which is vertically supported a rotatable barrel 11. A similar barrel 12 is mounted in bearings in a pivoted supporting arm 13, (Fig. 2) the barrel 12 when in normal position being substantially parallel to the barrel 11. The arm 13 is extended at its upper end to form a sleeve 14 to which is pivoted a rod 15 (Fig. 1) which passes loosely through a lug upon the sleeve 16 forming the upper end of the frame 10. A spring 18 surrounds the rod 110

15 and is secured between the lug upon the sleeve 16 and a nut 19 upon the end of the rod 15, said spring tending constantly to swing the barrel 12 toward the right, as viewed in Fig. 1. A loose spacing sleeve 20 surrounds the rod 15 and abuts against the lugs upon the sleeves 14 and 16, thereby securing the rotatable barrels 11 and 12 in spaced relation, while the yielding connection permits them to be temporarily separated at their upper ends, should necessity arise. Each of the barrels 11 and 12 has rigidly secured at its upper end, a disk 21 (Figs. 1, 3 and 5) formed with a plurality of recesses 22 each adapted to partially encircle and grip a bobbin presented thereto. Reference to Fig. 1 will show that the gripping members 21 grasp the bobbin between the butt and the bunch of waste 20 yarn left upon the cylindrical portion of the bobbin.

The barrels 11 and 12 may be formed with a plurality of flat sides as shown in Fig. 4 and in any event are provided with a plurality of longitudinally extending slots 23 within which blocks 24 (Fig. 1) are mounted to slide. A vertically extending stripper plate 25 is secured to each block 24 by screws extending therethrough into a threaded nut plate 26. This construction permits the plates 25 to be freely movable axially upon the barrels 11 or 12 while preventing their disengagement therefrom.

Each stripper plate 25 has at its upper end a lateral projection 27 having a recess 27^a (Fig. 9) therein substantially similar in contour to the recesses in the gripping members 21. At the lower end of each plate 25 there is also a slight lateral projection 28 and the lower edge of the plate 25 and the projection 28 is so disposed as to contact with one of the fixed cams 29 and 29^a (Figs. 1 and 2) mounted concentrically with the barrels 11 and 12. The cam 29 is secured to the frame 10 and the cam 29^a is mounted upon the pivoted support 13 and is movable therewith thus at all times retaining its concentric relation with the barrel 12.

50 A non-rotatable rod 30 is mounted to slide longitudinally in bearings within the barrel 11 and is provided, intermediate of its ends, with a laterally extending lug 31, (Fig. 1) adapted to project over the nut plate 26 of that stripper plate 25 which happens to be in operative position. The lower end of the rod 30 is secured to a cross arm 32 shown in dotted lines in Fig. 1 and is adjustable longitudinally thereon by lock nuts 33. A similar rod 34 extends through the barrel 12 and is pivoted at its lower end to the cross arm 32. The rod 34 is provided with a lateral projection 31 in the same manner as is the rod 30.

65 A cam roll 35 (Fig. 1) is secured to the

cross arm 32 between the rods 30 and 34 and coacts with a double-acting cam 36 mounted upon a cam shaft 37. A bevel gear 38 is also mounted upon the cam shaft and is driven by a pinion 39 secured to the driving shaft 40. This shaft may be connected with any convenient source of power by any suitable means such as the tight and loose pulleys 41 and 42 and the driving belt 43.

75 A shipper 44 is mounted to slide transversely in the frame of the machine and is provided with shipper fingers 45 by which the position of the belt may be controlled. A spring 46 (Fig. 7) is secured at one end 80 to the shipper and at its opposite end to a fixed part of the machine and tends constantly to throw the belt onto the loose pulley.

85 The means employed for giving an intermittent rotation to the barrels 11 and 12 comprises a one-tooth locking pinion 47 (Fig. 4) secured to the cam shaft 37 and cooperating with an intermittent gear 48 secured to the lower end of the barrel 11. 90 The barrel 11 is also provided with a spur gear 49 meshing with a similar gear 50 secured to the lower end of the barrel 12. Rotation of the pinion 47 by the cam shaft 37 will intermittently impart a partial rotation to the barrels 11 and 12 and between these partial rotations the barrels will be held in fixed angular position by the locking portion 51 of the pinion 47. In the position of the gears shown in Fig. 4 the 100 intermittent gear 48 has just completed its partial angular rotation and the locking portion 51 of the pinion has partially engaged and locked the gear 48 against further angular movement. This locking engagement will continue until the pinion 47 has substantially completed its revolution.

105 Inclined guides or supports 52 are provided for the bobbins, the guides upon the front side of the machine (shown to the 110 right in Fig. 1) being secured to a bracket 53 (Fig. 2) upon the frame 10, as by screws 53^a, while the guides upon the rear side are secured to the front guides by arched connections 54. Thus supported, movement of 115 the pivoted arm 13 will not result in separation of the guides 52. The guides 52 are extended horizontally toward the discharge end of the machine, as shown at 52^a to support the bobbins as they leave the stripping 120 mechanisms. The bobbins B are suspended by their butts on the guides 52 and are moved by gravity along the guides into proximity of the gripping devices 21. In addition to the gravity feed, a feeding finger 56 (Figs. 1 and 3) engages each bobbin as it approaches the gripping mechanism and pushes it positively forward within reach of the grippers 21.

125 The feeding finger 56 is part of a slotted 130

arm 57 which is mounted to slide upon a block 58 (Fig. 3) pivoted to the frame 10 at 59. In the end of the slotted arm 57 there is a bearing for a crank pin 60 secured by a crank arm 61 to the upper end of the crank shaft 62. The crank shaft 62 is suitably supported in bearings upon the frame 10 and has mounted upon its lower end a sprocket 63 (Fig. 1). A similar sprocket 64 is secured to the lower end of the cam shaft 37 and the sprockets are connected by a sprocket chain 65 so that the crank shaft 62 will make one revolution for each revolution of the cam shaft 37. The direction of rotation of the shaft 62 is such that the crank pin withdraws the feeding finger from contact with the bobbins during its return stroke and advances the same during its feeding stroke to positively push the bobbins forward to the gripping devices.

In order to prevent injury either to the feeding finger or to the bobbins in the event that one of the bobbins for any reason cannot be advanced to the gripping devices, I have provided a yielding connection between the crank pin and the feeding finger by forming one side of the slotted arm 57 as a separate member 66 (Fig. 3) pivoted to the arm 57 at 67. A stud 68 is mounted in the end of the arm 57 and passes freely through a hole in the corresponding end of the arm 66. A spring 69 surrounds the stud 68 and is suitably secured at one end thereto, being so disposed as to force the arms 57 and 66 normally into contact with each other. When the normal movement of the feeding finger is prevented, the spring 69 will yield and permit separation of the arms 57 and 66. After the obstruction is removed, the parts automatically return to their usual relative positions.

The operation of my machine as thus far described is as follows:—The bobbins B are suspended by their butts in the guides 52, the placing of the bobbins within these guides constituting the only manual labor required in the operation of the machine. The bobbins move gradually downward toward the gripping devices and are ultimately moved forward by the feeding finger 56 at the same instant that a coöperating pair of the recesses 22 upon the disks 21 approaches operative position. As the bobbin advances and is gripped between the disks 21, it is also partially encircled by a pair of projecting flanges 27 upon the stripper plates 25.

The fixed cams 29 are of such contour that the stripper plates reach their extreme upper limit of travel just before they are moved to operative position, and the cams are also so shaped, that the plates, when moved into operative position, are unsupported by the cams and are free to be moved downward in the slots 23 of the bar-

rels 11 and 12. As the plates 25 come into operative position, they stop below the projecting lugs 31 upon the sliding rods 30 and 34, which rods are immediately thereafter given a downward movement by the cam 36. This forces the stripper plates 25 downward and, as the projections 27 upon the plates encircle the cylindrical portion of the bobbin above the bunch of waste yarn thereon, the yarn is carried downward by the plates 75 and is thus separated from the bobbin.

As the stripping devices approach the lower limit of their travel, the feeding device operates to eject the stripped bobbin and to feed the next bobbin into stripping position. The stripped bobbins travel along the horizontal guides 52^a and may be thereafter disposed of by causing them to drop into a suitable receptacle or in any other desired way. During their passage through the machine, the lower ends of the bobbins B may be guided by additional guiding members 70 secured to the frame 10. It sometimes happens that a bobbin will not be properly advanced to the gripping device and will be caught between the projections separating the recesses 22 in the disks 21. In this event, the barrel 12 will yield and move to the left as viewed in Fig. 1, thus preventing breakage of any of the operative parts of the machine. As this yielding movement of the barrel 12 does not usually release the caught bobbin, I have provided connections by which the outward movement of the barrel can operate to stop the machine.

The shipper 44, previously referred to, is provided with a pair of slots 71 (Fig. 7) through which a pair of studs 72 are passed to support the shipper to slide upon the frame 10. In the upper side of the shipper 44 there is provided a notch 73 so located that when the belt is shifted onto the tight pulley, the notch 73 will be caught by a latch 74 pivoted at 75 to the frame 10. The latch 74 has secured thereto an arm 76 (Fig. 8) which extends over the outer end of an arm 77 securely fastened to the lower part of the sliding rod 34.

As shown in Figs. 6 and 7, the parts just mentioned are so adjusted that when the shaft 34 is in its normal position parallel to the shaft 30, the arm 77 will permit the latch 74 to engage the notch 73. When the rod 34 is swung outwardly, as in the event of a bobbin being caught between the gripping members, the end of the arm 77 will be raised and will in turn raise the arm 76 of the latch 74 and release the shipper. A screw 78 and lock nut 79 provide adjustment between the arms 76 and 77. It is therefore evident that outward movement of the barrel 12 and shaft 34 will normally release the shipper and stop the machine. It sometimes happens, however, that the yarn upon

a particular bobbin is so tightly wound that it cannot be forced off from the bobbin by the stripping plates 25. In this event the plates are dragged over the bunch and may 5 force the barrel 12 outwardly in the same manner as when a bobbin is caught between the gripping devices. It is not necessary to stop the machine under these conditions and accordingly the stop motion device previously described is so arranged that such outward movement of the barrel 12 will not release the shipper. This result is obtained by proper adjustment of the arm 77 upon the rod 34. When the rod 34 is in its extreme 10 upper position, as it will be during the feeding of the fresh bobbin into the machine, the arm 77 should be so located vertically that it can coöperate with the arm 76 and latch 74 to stop the machine if a bobbin is 15 caught by the grippers. As soon as the feeding operation is ended, however, the rod 34 begins its downward movement to strip the bobbin and in so doing, the arm 77 is 20 separated from the arm 76 so that the barrel 12 and the rod 34 may thereafter be swung 25 outwardly but the arm 77 will not raise the latch and release the shipper.

It should be understood that I do not limit this part of my invention to use with the 30 particular driving and shipping mechanism herein disclosed and that it is within the scope of my invention to connect the stopping devices herein described to release any form of driving device which it may be 35 found convenient to use in the machine.

Having thus described my invention it will be clear that many changes and modifications can be made therein by one skilled 40 in the art without departing from the spirit and scope thereof and I do not wish to be limited to the details herein disclosed, but

What I claim is:—

1. A bobbin stripper having in combination, means for supporting a bobbin, a 45 plurality of stripping devices, and means for moving said devices successively into operative position.

2. A bobbin stripper comprising a plurality of gripping and stripping devices, 50 and means for intermittently moving said devices in successive pairs into operative position.

3. A bobbin stripper comprising in combination, gripping and stripping devices, 55 and means for moving said devices in a continuous path alternately into operative and inoperative positions.

4. A bobbin stripper, having in combination, bobbin supporting means, a plurality 60 of pairs of stripping devices successively presented in operative position and movable longitudinally of the bobbins to strip the same, and means to return the stripping devices to their former longitudinal position 65 while they are out of operative position.

5. A bobbin stripper having in combination, bobbin supporting means, stripping devices mounted to slide axially in rotatable barrels, mechanism for intermittently partially rotating said barrels and for alternately locking them against rotation, means for positively moving said stripping devices longitudinally of the barrels to strip the bobbins while the barrels are locked with the stripping devices in operative position, 70 and means for returning the stripping devices to their former longitudinal position 75 while they are out of operative position.

6. A bobbin stripper, comprising a rotatable member, a stripping device on said member, means to alternately rotate said member and to lock the same in successive angular positions, means to give said stripping device its operative movement while said member is locked in a single position, 80 and means for gradually returning the stripping device to normal position as the member is advanced through successive angular positions.

7. A stripping device having in combination a member mounted to rotate in fixed vertical bearings, a second member normally parallel to the first member and mounted in bearings on a pivoted support, means for intermittently rotating the first member, 90 gears on said members by which the first member may drive the second member, a plurality of gripping devices and stripping devices mounted on said members and co-operating in successive pairs when in operative position, and means for moving the stripping devices longitudinally of the members to strip the bobbins.

8. A bobbin stripper having in combination a plurality of rotatable barrels, a plurality of pairs of stripping devices mounted to slide longitudinally of the barrels, fixed cams concentric with the barrels to move the stripping devices in one direction and reciprocating members to positively drive 110 the stripping devices in the opposite direction.

9. A bobbin stripper, having in combination a pair of vertically supported rotatable barrels, a disk on each barrel having a plurality of gripping recesses therein, a corresponding number of vertically movable stripping devices supported on each barrel, cams to raise said stripping devices, and members positively actuated to force said 115 stripping devices downward to strip the bobbins.

10. In a bobbin stripper, in combination a pair of vertically mounted rotatable barrels, a disk on each barrel having a plurality 120 of gripping recesses therein, a pair of sliding blocks mounted in longitudinal slots in said barrels, each block having a plate with a radial projection adapted to partially encircle the barrel of a bobbin, and means for 125 130

alternately moving the blocks in opposite directions.

11. In a bobbin stripper, a supporting frame, longitudinally slotted barrels rotatable therein, means to rotate the barrel, a plurality of stripping devices mounted on the barrel and longitudinally movable in the slots, means for moving the stripping devices in one direction and a sliding rod for 10 moving them in the opposite direction, said rod being non-rotatably mounted concentric with said barrel and having a lug projecting from one side thereof and contacting with each of said stripping devices as the latter are rotated into operative position, said rod 15 acting through the lug to move the stripping devices axially of the slotted barrel to strip a bobbin.

12. A bobbin stripper having in combination a pair of rotatable coöperating gripping members, guides for the bobbins and intermittently operated mechanism for sliding the bobbins along the guides into the path of the rotatable gripping members.

25 13. In a bobbin stripper, in combination, a pair of rotatable coöperating gripping members, guides upon which a plurality of bobbins may be suspended by their butts, and means for intermittently sliding said 30 suspended bobbins along the guides into the path of the rotatable gripping members.

14. A bobbin stripper having in combination a pair of coöperating grippers, stripping mechanism, guides for the bobbins, 35 means for feeding the bobbins from said guides to said grippers and stripping mechanism, and devices for driving said feeding means, the driving devices and feeding means being yieldingly connected and temporarily separable under excessive pressure.

40 15. In a bobbin stripper, in combination, a supporting structure upon which a plurality of bobbins may be suspended by their butts, gripping and stripping mechanism located intermediate the ends of said structure, and means for intermittently feeding the suspended bobbins along the supporting structure to and past the gripping and stripping mechanism.

50 16. A bobbin stripper, having in combination a pair of gripping members mounted to rotate in opposite directions on substantially parallel axes, means to support a bobbin, and means to advance said bobbin into the path of the rotating gripping members.

55 17. In a bobbin stripper, feeding mechanism comprising a pivoted block, a slotted

arm mounted to both pivot and slide on said block, and a rotatable shaft having a crank arm and crank pin thereon, said slotted arm 60 having a bearing for said pin and being operable thereby.

18. In a bobbin stripper, feeding mechanism comprising a pivoted block, a slotted arm mounted to both pivot and slide on said 65 block, and a rotatable shaft having a crank arm and crank pin thereon, said slotted arm having a bearing for said pin and being operable thereby, the two sides of the slotted arm being pivoted together and yieldingly 70 connected to be separable under excessive strain.

19. A bobbin stripper, having in combination gripping members, stripping mechanism, means for driving the gripping members and the stripping mechanism, and connections between the gripping members and the driving means whereby abnormal separation 75 of the gripping members will disengage the driving means.

20. A bobbin stripper, having in combination grippers, stripping mechanism, driving means therefor, and a stop motion device rendered operative by abnormal separation 85 of the grippers when the stripping mechanism is at the upper limit of its travel only.

21. A bobbin stripper, having in combination a pair of grippers yieldingly held in spaced relation, stripping mechanism, driving means for the grippers and stripping 90 mechanism, a shipper, a latch to hold said shipper in operative position, and means actuated by abnormal separation of the grippers to disengage said latch and release the shipper.

22. A bobbin stripper, having in combination a pair of grippers yieldingly held in spaced relation, stripping mechanism movable longitudinally of the bobbin, driving means, devices to render said driving means 100 operable and a release for said devices actuated by abnormal separation of the grippers when the stripping mechanism is in its highest position but unaffected by such separation after the descent of the stripper has 105 begun.

In testimony whereof I have hereunto set my hand, in the presence of two subscribing witnesses.

EPPA H. RYON.
